UNITED STATES PATENT OFFICE.

RUSSELL A. TRACE, OF DAYTON, OHIO, ASSIGNOR TO BUCKEYE IRON AND BRASS WORKS,
OF DAYTON, OHIO, A CORPORATION OF OHIO.

MEANS FOR FORMING OIL-CAKES.

1,336,171.

Specification of Letters Patent.

Patented Apr. 6, 1920.

Original application filed July 30, 1917, Serial No. 183,430. Divided and this application filed January 7, 1918. Serial No. 210,744.

To all whom it may concern:

Be it known that I, RUSSELL A. TRACE, a citizen of the United States, residing at Dayton, in the county of Montgomery and State of Ohio, have invented certain new and useful Improvements in Means for Forming Oil-Cakes, of which the following is a specification, reference being had therein to the accompanying drawing.

10 This invention relates to means for forming oil cakes, and its principal object is to improve the operating mechanism for the charge box and the construction of the charge box itself.

15 In forming oil cakes the meal is usually dropped from a cooker into a charge box which is then moved so as to convey its charge to the press which forms the cakes. The present invention provides an improved 20 mechanism for moving the charge box, the construction being such that a single lever may control the entire movement of the charge box, the return movement of the box being entirely automatic.

25 An additional object is to provide a construction whereby the operator is not required to lay the usual press cloth over the mold box of the press, but on the other hand the press cloth is carried by an element of 30 the charge box and the construction is such that movement of the box to carry its charge of meal into the mold box of the press will draw the press cloth smoothly over the bottom of the mold box and on the return 35 movement of the charge box the press cloth will be automatically drawn smoothly over the meal.

This application is a division of a prior 40 application, Serial No. 183,430, filed July 30, 1917.

In the accompanying drawings,

Figure 1 is a side elevation of the charge box and its operating mechanism showing the parts in normal position between operations;

Fig. 2 is a similar side elevation, but showing the charge box advanced into the press ready to deposit its charge of meal in the mold box;

50 Fig. 3 is a fragmentary plan view of the mechanism of Figs. 1 and 2; and

Fig. 4 is a detail view, mostly in section, showing the hydraulic cylinder which operates the charge box and valve mechanism

controlling the movement of the piston in this cylinder.

Referring first to Fig. 1 it will be understood that the meal is brought to the machine from a tempering or cooking kettle which is not shown, it being no part of the invention.

From the kettle the meal is deposited in a hopper 1 which is directly over the charge box or conveyer 2. A hydraulic cylinder 3 serves to move the charge box from the position of Fig. 1 to that of Fig. 2. Valve 4 controls the movement of the piston in cylinder 3 and a handle 5 serves to operate the valve mechanism.

The charge box operating mechanism as a whole is carried on a frame 11 having the 70 hydraulic cylinder 3 at one end and the charge box 2 at its other end. The charge box is provided with an upper apron 12 fast to and moving with the box, this apron passing directly under the hopper 1 and 75 preventing escape of meal therefrom except when the charge box is under the hopper. As usual the charge box has sides and ends, but no top or bottom and what is in effect a bottom is provided by a second lower apron 80 13 moving frictionally with the charge box through part of the movement of the latter. This apron is carried by rollers 14 and arms 15, the latter having circular extensions 17 at their upper ends and being pivoted on 85 pins 16. Comparing Figs. 1 and 2 it will be seen that the movement of the charge box carries the apron 13 with it until the arms 15 engage a projecting end of the mold box 8, whereupon the apron 13 stops though the 90 charge box may continue its movement. To insure the proper movement of the apron 13 it is provided with a depending bracket 18 from which links 19 extend to the pivoted arms 15. These links compel the apron 13 95 and the arms 15 to move together. The return of the charge box to the position of Fig. 1 also restores the apron 13 to its normal position and to make certain that this return of the apron is properly made it is provided at its left hand end with a lug or projection 20 positioned to be engaged by the end 54 of the charge box, whereby the apron is positively returned to its normal position.

To operate the charge box the hydraulic cylinder 3 is provided with a piston 24, as shown in Fig. 4, this piston being carried

by a rod 25 which passes entirely through the charge box 2. One end of the cylinder 3 may be provided with a stuffing box 26 and it is pierced near its opposite ends for pipes 27 and 28 to permit entrance of the liquid employed. These pipes are both connected to the valve mechanism 4. The liquid under pressure enters the valve 4 through a port 30 and is discharged therefrom through a port 31.

The valve stem 29 is provided with a cut away portion 33 and the entrance and exit ports 30 and 31 may have enlarged portions 32 and 35 so as to permit the passage of the liquid. A chamber 34 at the point where the pipe 28 enters the valve is connected with the chamber 35 by the cut away portion 33.

In the position of the parts shown in Fig. 4 the pipe 28 and the exit pipe 31 are connected by the cut away portion 33 and the passage from entrance port 30 to pipe 27 is open. When the valve stem 29 is moved to the right in this figure it will connect the entrance port 30 to the pipe 28 and then 20 movement of the piston 24 and piston rod 25 occurs. It will be observed that the construction is such that pipe 27 is always open to the liquid pressure from entrance port 30, but piston 24 is a differential piston and the 25 operation of the valve mechanism will be obvious.

To actuate the valve 4 the handle 5 is shown in Fig. 1, this being pivoted on a pin 41 carried by the frame 11 and having a 30 depending arm 42 ending in the disks 43 on opposite sides of the valve stem 29 and moving between collars 44 around the valve stem. An extension 45 of the handle 5 has a notch therein arranged to be engaged by a 35 trip lever 46 which is pivoted on the machine frame by a pin 47 and is provided with a spring 48 tending to move it to latching position.

When the handle 5 is elevated from the 40 position of Fig. 1 to that of Fig. 2 the latch 46 is moved over the handle extension 45 by its spring 48, thus retaining the lever 5 elevated and thereby causing liquid under pressure to pass through pipe 28 to the left 45 of piston 24 in Fig. 4.

To release the handle 5 the charge box 45 apron 12 is provided with a flange 53 having a slot 52 in which rides an adjustable pin 51. As the charge box moves to the 50 right the pin 51 will finally engage the right hand end of lever 46 and depress it, thus releasing the handle lever 5 and permitting its return to the position of Fig. 1. This connects the pipe 28 with the exit pipe 31 in Fig. 4 and then the liquid pressure through pipe 27 immediately returns the piston 24 and charge box 2 to their normal positions.

The piston rod 25 has a slight lost motion connection with the charge box. It passes completely through the left hand end 55 54 of

the box and the right hand end thereof, the connection permitting a slight relative movement of the piston rod relative to the charge box. The end 54 of the charge box carries a nut 57 and slightly spaced away 70 from this is a collar 56 fast on the piston rod 25. On the right hand end of the piston rod is a nut 59 and slightly spaced away from this is a collar 58. When the piston rod 24 moves to the right in Fig. 1 the first 75 element of its movement is occupied in taking up the lost motion between collar 56 and nut 57 and only after this is taken up does the charge box start to move. As seen in Fig. 2 the collar 58 is spaced somewhat away 80 from the end of the charge box and the return movement of piston rod 25 must take up this slight lost motion before return movement of the charge box begins. This lost motion has to do with the placing of 85 the press cloth as will be later explained.

Carried on the side of the charge box is a bracket 60 and a rod 61 passes through the end of this bracket entirely across the front end of the charge box. The press cloth 62 is 90 adapted to be placed over this rod 61 and is held in position as the charge box moves by a spring arm 63. This arm is carried on a pin 64 on the charge box and it surrounds piston rod 25 between collars 58 and 59. 95 When the piston rod moves to the right in Fig. 1 the first element of its movement permits the spring finger 63 to move to the right against the press cloth, as indicated in Fig. 2, the spring pressure serving to 100 carry the press cloth with the rod 61 into the press.

It is, of course, desired that the press cloth shall be laid smoothly across the bottom of the mold box 8 and to this end the 105 charge box has two depending plates 65 pivoted on a pin 64 at the opposite sides of the charge box. These plates or arms abut against flanges 66 carried by the apron 13 and the arms 65 are prevented from rotating 110 in a clockwise direction from the position of Fig. 1 in any desired manner, as, for example, by projections from pin 64. Movement of these arms 65 in the opposite or counterclockwise direction is permitted. As 115 the charge box moves to the right from the position of Fig. 1 the depending arms 65 engage the press cloth and carry it smoothly over the mold box bottom, as shown in Fig. 2. From this figure it will be seen that the 120 lower ends of arms 65 are at such a height as just to clear the bottom of the mold box 8.

When the charge box begins its return movement from the position of Fig. 2 the collar 59 first engages the spring fingers 63 125 and restores them to the position of Fig. 1, thus releasing the press cloth 62. Of course, the weight of the meal holds the press cloth on the mold box 8 and therefore the return movement of the charge box causes the rod 130

61 to draw the press cloth smoothly over the meal. When the charge box reaches the normal position, as shown in Fig. 1, the workman may take the end of the press cloth at 5 the left in Fig. 2 and fold it smoothly over the remaining portion of the meal. Thus, the operation of the machine automatically places the press cloth in proper position on the press and folds one end of it over the 10 meal. It is necessary for the workman to fold the remaining end only over the meal, whereupon the operation of the press may take place.

While I have shown and described certain features as constituting my invention, 15 it will be understood that parts have been shown for purposes of illustration only, and that I do not desire to be limited to such details, as obvious modifications will occur to 20 a person skilled in the art.

Having thus fully described my invention, what I claim as new and desire to secure by Letters Patent, is:—

1. In a cake former, the combination, with 25 means for dumping a predetermined quantity of meal, of a carrier therefor, a cloth on said carrier adapted to receive said meal, a charge box for transporting said meal to said cloth in the mold box of a press, and 30 a cloth holder for drawing said cloth over the face of said meal.

2. In a cake former, the combination, with 35 a conveyer for carrying meal to a mold box, of a press cloth holder on said conveyer acting to draw said cloth over the meal on the return of said conveyer.

3. In a cake former, the combination, with 40 a conveyer for carrying meal to a mold box, devices for holding a press cloth on said conveyer, said devices acting to draw the cloth under the meal in the mold box on the forward movement of the conveyer and to draw the cloth over the meal on the return movement of the conveyer.

4. In a cake former, the combination, with 45 a conveyer for carrying meal to a mold box, of a press cloth holder for detachably holding a cloth on said conveyer, and a cloth releaser actuated as the conveyer is returned.

5. In a cake former, the combination, with 50 means to admit a predetermined quantity of meal from a hopper onto a conveyer, a seal for said hopper acting to prevent further exit of the meal, a charge box to convey said meal onto a cloth in a mold box, and a cloth holder acting to fold said cloth over the top of said meal on the return of said conveyer.

6. In a cake former, the combination, with 55 means to admit a quantity of meal from a hopper onto a conveyer, of a seal for said hopper acting to prevent further exit of the meal, a hydraulic pump for advancing the conveyer to a mold box, a press cloth holder adapted to draw the cloth across the

bottom of said mold box with the meal thereon, the cloth serving to close the open side of said mold box in the direction of the entrance of the meal, tripping mechanism on said conveyer acting to reverse said 70 hydraulic actuating means, thereby causing said conveyer to move in the opposite direction to its initial position.

7. In a cake former, the combination, with 75 a meal support upon which meal falls from a hopper, a seal to close the mouth of said hopper to prevent the further exit of meal, a cloth holder acting to hold a cloth positively in position while said meal is conveyed to the mold box and to draw it over 80 the top of the meal upon the return of the conveyer, hydraulic means for actuating the conveyer, and connections on said meal support to effect the reversal of the direction of movement of said hydraulic means. 85

8. In a cake former, the combination, with 90 a conveyer upon which meal falls from a hopper, of a seal to prevent the exit of meal from said hopper when said conveyer has received its appropriate amount of meal, hydraulic means for moving said conveyer to the edge of a mold box, thus forming one wall of said mold box by the end of the conveyer, adapted to move a cloth across said mold box, means to reverse the direction 95 of said conveyer, whereby it and said cloth holder are returned to their initial positions, said cloth being thereby folded over the top of said meal and the mouth of said hopper exposed to permit the deposit of an 100 additional quantity of meal.

9. In a cake former, the combination, with 105 a carriage with a conveyer traveling thereon adapted to move to the edge of a mold box and close one side of said mold box, of a clamp for a cloth supported by said conveyer, said clamp adapted to carry said cloth to the farther edge of said mold box and turn said cloth over the top of said meal, hydraulic means for advancing said conveyer and cloth holder in one direction, means to reverse the direction of movement of said hydraulic means to return said conveyer and said cloth holder to their initial 110 positions, said hydraulic means consisting 115 of a cylinder with a differential piston therein, the greater area of liquid pressure being on the side of said piston more distant from the conveyer.

10. In a cake former, the combination, 120 with means for conveying meal to a mold box of a press, of a cloth holder adapted to fold a cloth upon which said meal rests over the top of said meal, hydraulic means for actuating said conveyer in one direction, means 125 for reversing said movement and returning said conveyer in the other direction, consisting of a differential piston connected to said conveyer adapted to present its larger area to the thrust of the liquid to move said con- 130

veyer in the first direction and to exhaust the liquid from the side of the larger area of said piston for movement in the other direction when the liquid acts upon the 5 smaller diameter of said piston to effect such return.

11. In a cake former, the combination, with a conveyer having a cross bar over which a press cloth may be placed, a cloth 10 holder controlled by movement of said conveyer for holding the cloth against said cross bar, whereby the movement of said conveyer will draw the press cloth over a mold box with the meal resting on the cloth, said 15 connections to release the press cloth during the return movement of the conveyer, whereby the cross bar draws said cloth over the charge of meal in the mold box.

12. In a cake former, the combination, 20 with a conveyer, and hydraulic means for moving it to convey a charge of meal to a mold box, said means including a cylinder and valve mechanism controlling access of liquid to said cylinder, of a cross bar carried by said conveyer on which a press cloth 25 may be placed, spring fingers for holding said press cloth on said cross bar, and connections controlled by movement of said conveyer, for engaging said spring fingers 30 with said cross bar during the outward movement and disengaging said fingers from said cross bar during the return movement of said conveyer, whereby the press cloth is folded over the charge of meal in the mold 35 box.

13. In a cake former, the combination, with a conveyer and an apron constituting the bottom of said conveyer, a roller and a pivoted arm on which said apron is carried, 40 means to move said conveyer to carry a charge of meal into a mold box, said movement carrying the apron bodily and fric-

tionally with said conveyer until said pivoted arm engages a wall of said mold box, said apron having a projection engaging 45 said conveyer to return said apron positively to its normal position.

14. In a cake former, the combination, with a charge box having end plates, of a driving rod for said box passing loosely 50 through both said end plates, lost motion connections whereby said rod drives said conveyer, and a cross bar carried by said conveyer and on which a press cloth may be placed, said lost motion connections permitting a relative motion between said driving rod and said charge box, whereby to hold or release the press cloth on said cross rod.

15. In a cake former, the combination, 60 with means to admit a predetermined quantity of meal from a hopper onto a conveyer, a seal for said hopper acting to prevent further exit of the meal, a charge box to convey said meal onto a cloth in a mold box, a cloth 65 smoother acting to spread the cloth in the charge box in the outward movement of the conveyer, and a cloth holder acting to fold said cloth over the top of said meal on the return of said conveyer. 70

16. In a cake former, the combination, with means to admit a predetermined quantity of meal from a hopper onto a conveyer, a seal for said hopper acting to prevent further exit of the meal, a charge box to convey 75 said meal onto a cloth in a mold box, a plurality of plates pivoted on the conveyer and acting to spread the cloth in the charge box in the outward movement of the conveyer, and a cloth holder acting to fold said cloth 80 over the top of said meal on the return of said conveyer.

In testimony whereof I affix my signature.
RUSSELL A. TRACE.
